ATTORNEY

UNITED STATES PATENT OFFICE

2,517,190

BRAKE BEAM FULCRUM

Norman Flesch, Chicago, Ill., assignor to American Steel Foundries, Chicago, Ill., a corporation of New Jersey

Application May 9, 1947, Serial No. 747,055

8 Claims. (Cl. 188—233)

1

This invention relates to railway brake beams and more particularly to a novel form of double jaw, or fulcrum member for connecting the beam to associated actuating means and balance means.

An object of the invention is to devise a double jaw of novel form with a view toward simplifying the assembly thereof with the beam.

At present, the double jaw is formed in two pieces which are riveted together on a brake beam. The overlapping portions of the two pieces at their point of connection to each other and to the brake beam are usually not close fitting, complicating the assembly thereof. In use, these pieces tend to rock and slide against each other, exerting bending stresses on the connecting rivets and loosening the connection.

It is the specific object of this invention to obviate these difficulties by providing a one-piece double jaw of simple, rugged construction, the double jaw being formed and arranged so that it may be sleeved over the enlarged cylindrical trunnion end of the beam and snugly fitted onto the flat portion of the beam and securely fastened thereto.

A still further object of the invention is to devise a one-piece double jaw of such form that it may be readily applied to brake beams now in use. These and other objects of the invention will become apparent from the description and the drawings, wherein:

Figure 1 is a top plan view of a brake beam showing the manner in which the novel double jaw is applied thereto, the jaw being illustrated at its assembled position in solid lines and at its preassembled position in phantom lines.

Figure 2 is a sectional view taken on the line 2—2 of Figure 1.

Referring to the drawings in detail, the invention is illustrated as applied to a brake beam of usual design, generally indicated at 2 (Figure 1), said beam comprising a flat bar portion 4 which is rectangular in cross section. At each end of the portion 4 is provided an enlarged end portion of a diameter greater than the thickness of said flat bar portion 4 and comprising an annular collar 6 from which projects a cylindrical trunnion 8 of reduced diameter with a bushing 10 fitted thereon, the trunnion affording a pivot for a brake head and supporting hanger (not shown).

The trunnion is herein illustrated as comprising several stepped-up portions. However, if desired, it may be of constant diameter from end to end, as will be understood by those skilled in the art.

The feature of the invention is the provision of

55

2

a one-piece double jaw or fulcrum member, generally indicated at 12. The member 12 is of skeletal construction and comprises intermediate its ends a body portion including spaced horizontal top and bottom webs 14 and 16 widened as at 18 and 20, respectively. Between the top and bottom webs adjacent one of the ends thereof extends a transverse web 22 joining said top and bottom webs and defining therewith a horizontal slot 24 dimensioned to snugly admit said flat rectangular portion 4 of the brake beam therein in the assembled position of the brake beam and double jaw member as may be seen in Figure 2 and as hereinafter described.

15 The top and bottom webs at the ends remote from said transverse web 22 are arcuately formed as at 26 and 28, respectively. These ends of said webs are joined by spaced upstanding lugs 30, 30 which are transversely arcuately recessed at their rear and form with said top and bottom webs a substantially circular opening 32 extending transversely through said member, the opening being of a diameter greater than said collar 6. The opening 32 communicates with said slot 24 and accommodates sleeving of the fulcrum member over the collar 6 onto the flat portion of the beam, as hereinafter described. The lugs 30, 30 form a jaw and are provided with aligned bushed openings 34, 34 affording a pivotal connection for a balance hanger (not shown). The juncture between the lugs 30, 30 and said top and bottom webs is reinforced and stiffened by a plurality of vertical arcuate ribs 36, 36.

On the other ends of the webs 14 and 16 is formed another jaw comprising spaced vertical ears or lugs 40, 40, said lugs merging at their inner ends into said top and bottom and transverse webs. The lugs 40, 40 are provided with aligned bushed openings 42, 42 affording a pivotal connection for a brake lever of associated brake rigging (not shown).

To assemble the double jaw member with the brake beam, the double jaw is positioned in a manner as shown in Figure 1 in phantom lines wherein the opening 32 is axially aligned with the trunnion. The double jaw member is then moved axially onto the trunnion and over the collar, the opening 32, as hereinbefore mentioned, being of larger diameter than the collar and accommodating such movement. After the double jaw member is passed over the collar, the flat portion 4 of the beam is entered into the slot 24 by moving the double jaw member transversely of the beam until the flat portion of the beam is completely entered into slot 24, at which time the

widened portions 18 and 20 of said top and bottom webs snugly embrace said portion 4 of the beam and one side of the portion 4 abuts as at 46 (Figure 2) against said transverse web 22 of the double jaw. To complete the assembly, the double jaw is removably secured to the brake beam as by rivets 48, 49 passing through aligned openings in the portion 4 and said widened portions of the top and bottom webs of the fulcrum member.

It is to be understood that I do not wish to be limited by the exact embodiment of the device shown which is merely by way of illustration and not limitation as various and other forms of the device will, of course, be apparent to those skilled in the art without departing from the spirit of the invention or the scope of the claims.

I claim:

1. In combination, a brake beam comprising a flat bar portion and a cylindrical end portion of a diameter greater than the thickness of said bar portion, a double jaw member having a jaw at each end adapted for connection to associated brake rigging elements and comprising intermediate said jaws a body portion having a slot snugly receiving said flat bar portion therein, a substantially circular opening extending transversely through said body portion at one end of said slot, said opening being larger than the diameter of said end portion and adapted to accommodate sleeving of said double jaw member onto and off said flat bar portion over said end portion by accommodating passage of the same therethrough in the assembly and the disassembly of said member with respect to said beam, and means removably securing said double jaw member to said bar portion of said beam.

2. In combination, a brake beam comprising a flat portion of rectangular cross section and a cylindrical portion at the end of said flat portion of a diameter greater than the thickness of said flat portion, a double jaw member removably connected to said beam and comprising a transverse slot intermediate its ends snugly receiving said flat portion therein and affording a mounting for said member on said beam, a circular opening through said member communicating with said slot and of a diameter greater than said cylindrical portion, said opening being adapted to accommodate insertion and removal of said member onto and off said flat portion over said cylindrical portion, a jaw at each end of said member for connecting the same to associated brake elements, and means connecting said member with said beam.

3. In a combination, a brake beam double jaw member comprising spaced webs intermediate its ends, a transverse web between said spaced webs interconnecting the same and defining a slot therewith, a pair of lugs at each end of said member connecting the adjacent ends of said spaced webs, one of the ends of said spaced webs being arcuately formed and with the associated lugs defining an opening communicating with said slot, a brake beam comprising a flat bar portion and an end portion, the former being adapted to be snugly received within said slot for mounting said member thereon and the latter being of a greater radial codimension than said flat portion but smaller than said opening and adapted to pass through said opening to permit sleeving of said member onto and off said flat portion in assembling and disassembling said member with respect to said beam.

4. The combination with a brake beam having

a flat portion and a cylindrical portion at one end of said flat portion of a diameter greater than the thickness of said flat portion; of a double jaw member sleeved over said cylindrical portion onto said flat portion and comprising a slot intermediate the ends thereof snugly receiving said flat portion therein, an opening extending transversely through said member adjacent one end thereof and communicating with said slot, said opening being larger than the diameter of said end portion for accommodating assembly and disassembly of said member with said beam by permitting said member to be sleeved over said end portion onto and off said flat portion.

5. In combination, a brake beam having a flat portion with a cylindrical end of a diameter greater than the thickness of said flat portion, a double jaw comprising an elongated member with a jaw at each end and having intermediate its ends a complementary slot receiving said flat portion therein, an opening at one end of said slot of a diameter greater than said cylindrical portion and extending through said member axially of said beam, said opening accommodating insertion or removal of said member over said cylindrical portion in assembling and disassembling said member with said beam.

6. In combination, a brake beam comprising a flat bar with a cylindrical end portion of a diameter greater than the thickness of said bar portion, a member for connecting said beam to associated brake rigging elements comprising an elongate body with a pair of jaws thereon, a slot and a communicating opening extending transversely through said body, said slot snugly receiving said flat portion therein, said opening being larger than the diameter of said end portion and accommodating insertion and removal of said member onto and from said flat portion of said beam over said cylindrical portion.

7. A double jaw member comprising a pair of spaced horizontal webs and an interconnecting vertical web defining therewith a horizontal slot, a pair of lugs at each end of said member connected to said webs, said horizontal webs being arcuately formed at one end and with the adjacent lugs defining an opening extending transversely of said member and communicating with said slot, said member being adapted to be sleeved onto an associated brake beam over a cylindrical end portion thereof and onto a flat bar portion thereof.

8. In combination, a brake beam comprising a flat portion and an enlarged nonflat end portion, a double jaw member comprising a complementary slot receiving said flat portion therein, and means connecting said double jaw member to said flat portion, said member having an opening communicating with said slot and complementary to said end portion for reception therein during assembly and disassembly of said double jaw member with said beam.

NORMAN FLESCH.
